208,430

APPARATUS FOR MARKING METALS

Dean A. Marshall, 13389 W. 23d Place,
Golden, Colo. 80401

Filed Mar. 14, 1966, Ser. No. 1,462

Term of patent 14 years

(Cl. D54—13)

FIGURE 1 is a perspective view of an apparatus for marking metals, showing my new design;

FIGURE 2 is a plan view of the apparatus shown in FIGURE 1, said view being rotated substantially 180° from the view of FIGURE 1;

FIGURE 3 is a front elevational view of the apparatus shown in FIGURE 2;

FIGURE 4 is a side elevational view of the apparatus shown in FIGURE 3;

FIGURE 5 is a rear elevational view of the apparatus shown in FIGURE 2; and

FIGURE 6 is a bottom plan view of the apparatus shown in FIGURE 1.

I claim:

The ornamental design for an apparatus for marking metals, as shown and described.
